CLAIM

The ornamental design for a combined container and applicator for polish in the form of paste, as shown and described.

DESCRIPTION

FIG. 1 is a perspective view of a combined container and applicator for polish in the form of paste showing my new design;

FIG. 2 is a front elevational view;

FIG. 3 is a rear elevational view;

FIG. 4 is a top plan view;

FIG. 5 is a bottom plan view;

FIG. 6 is a left side elevational view;

FIG. 7 is a right side elevational view; and,

FIG. 8 is a perspective view of the combined container and applicator for polish in the form of paste with the top and bottom separated so as to expose the applicator and container.
